UNITED STATES PATENT OFFICE.

ROSWELL H. JOHNSON, OF PITTSBURGH, PENNSYLVANIA.

METHOD OF EXTRACTING OIL FROM OIL-BEARING ROCK OR SAND.

1,083,018.

Specification of Letters Patent.

Patented Dec. 30, 1913.

Application filed February 3, 1913. Serial No. 745,998.

To all whom it may concern:

Be it known that I, ROSWELL H. JOHNSON, a citizen of the United States, resident of Pittsburgh, in the county of Allegheny and

5 State of Pennsylvania, have invented a new and useful Improvement in Methods of Extracting Oil from Oil-Bearing Rock or Sand; and I do hereby declare the following to be a full, clear, and exact description

10 thereof.

My invention relates to a method of extracting oil from oil-bearing rock or sand in cases where the oil has ceased to flow naturally from the wells drilled into such rock or 15 sand, or where pumping means have altogether failed or are ineffectual to extract the oil in paying quantities.

In many cases where the well is drilled to the bottom of the oil-bearing sand or rock 20 in the usual manner, there is a body of water, generally salt, below generally termed the water-sand. By the usual method of pumping, a quantity of the oil can be extracted from the rock or sand, but after a 25 time it will be found that the yield is very small, and that the oil at the lower part of the rock or sand is difficult to extract, owing to the fact that there is not sufficient gradient to cause flow toward the well.

30 The object of my present invention is to provide a method by means of which a gradient can be developed which will tend to cause the oil which cannot be extracted by the ordinary method of pumping to flow 35 from the oil-bearing rock or sand to the well, so that it can be pumped therefrom.

To these ends my invention consists, generally stated, in drilling the well through the oil and a certain distance into the water-sand, pumping up the oil and a certain amount of water and in this way creating a gradient toward the hole which will cause the oil in the rock or sand to be carried along the top of the water toward the hole, 45 the water moving faster than the oil, and so aiding the movement of the oil by adhesion.

In the accompanying drawing I have illus-

trated the manner in which my method is carried out in which—

Figure 1 shows the well drilled to the 50 bottom of the oil-bearing rock or sand with the water below; Fig. 2 indicates how the oil collects at the bottom of the oil-bearing rock upon the water; and Fig. 3 shows the well drilled deeper and how by my method 55 the slope or gradient is formed for carrying the oil toward the well.

Referring to Fig. 1, which shows the well drilled to the bottom of the sand in the usual way, the numeral 4 represents the inclosing 60 shale or other non-oil bearing rock; the numeral 6 the sand with its original oil content, and 5 the underlying water.

In Fig. 2 is shown the result of pumping in the ordinary manner to remove the oil 65 from the oil-bearing sand or rock 6, which has been to exhaust the oil from the upper portion of said sand or rock leaving the oil indicated by the numeral 7 at the lower portion of the sand or rock and directly above 70 the water 5 due to the fact that the gradient is not sufficient to move it toward the hole in sufficient quantities for profitable operation.

Fig. 3 shows the action which takes place when my process is in operation in which 75 the pumping action in the well lifts the oil and a certain amount of water and in so doing a gradient or slope has been provided which tends to drain the oil in the lower part of the oil-bearing rock or sand toward 80 the hole, said oil resting on the water and as the water moves faster than the oil, the water aids the movement of the oil by adhesion.

In the practice of my invention the well is 85 originally or subsequently drilled to such a depth into the water-bearing sand as to yield the desired amount of water. In this manner I am enabled to extract oil which would otherwise remain at the lower portion of the 90 oil-bearing rock or sand, and which it is impracticable to extract by the ordinary pumping method, and many wells have been abandoned for this reason. Where there is not

sufficient gradient to cause oil to move toward the hole, it will remain confined in the lower portion of the oil bearing rock or sand, and by creating a sufficient gradient 5 by my method, this oil will flow from the lower portion of the oil-bearing rock toward the hole and can then be readily removed.

What I claim is:

The method of extracting oil from oil-bearing rock or sand, consisting in drilling 10 the well through the oil-sand and a certain

depth through the water-sand, pumping up oil and a certain amount of water, and so forming a gradient for the oil toward the well, and thereby aiding the movement of 15 the oil toward the well.

In testimony whereof I, the said ROSWELL H. JOHNSON, have hereunto set my hand.

ROSWELL H. JOHNSON.
